PERCUSSIVE TOOL

William A. Smith, Sr., Phillipsburg, N. J., assignor
to Ingersoll-Rand Company, Jersey City, N. J.,
a corporation of New Jersey

Application June 29, 1939, Serial No. 281,814

6 Claims. (Cl. 125—33)

This invention relates to percussive tools, and more particularly to an internal combustion engine operated percussive tool of the type in which the working implement is capable of free reciprocal movement with respect to the element actuating it.

One object of the invention is to construct a rugged, compact and powerful percussive tool that may be conveniently manipulated and guided with respect to the work and which will be capable of fulfilling all the requirements of a tool of this character in the various positions which it may occupy in practice.

Other objects will be in part obvious and in part pointed out hereinafter.

In the drawings accompanying this specification and in which similar reference numerals refer to similar parts,

Figure 1 is a side elevation of the percussive tool constructed in accordance with the practice of the invention.

Figure 2 is an elevation, partly in section, of the percussive tool.

Figure 3 is a transverse view, in section, taken through Figure 1 on the line 3—3 showing more particularly the interior of the percussive element.

Figure 4 is a transverse view, in section, taken through Figure 3 on the line 4—4.

Figure 5 is a view similar to Figure 3 taken on the line 5—5 in Figure 1 and showing the interior of one of the power cylinders.

Figure 6 is a transverse fragmentary view, in section, taken through Figure 5 on the line 6—6, and

Figure 7 is a view taken through Figure 6 on the line 7—7.

Referring more particularly to the drawings, 20 designates, in general, a percussive tool, and 21 a working implement which the percussive tool is intended to actuate.

In the form of the invention illustrated the percussive tool 20 comprises a crank casing 22 supporting upon its rearward end a fuel tank 23 and at its forward end a pair of depending engine cylinders 24 and 25 and a percussive cylinder 26 arranged between the engine cylinders and axially of the percussive tool 20.

In accordance with the practice of the invention, the fuel tank, which may be rigidly secured to the crank casing 22 in any suitable manner, serves as a support for a handle 27 whereby the percussive tool may be guided. The fuel tank is accordingly provided with an internal rib 28 which extends entirely therethrough and has a

bore 29 to accommodate a bolt 30 upon the ends of which are disposed grip members 31.

At the upper end of the fuel tank is a filling opening 32 normally sealed by a plug 33 and between the fuel tank and the crank casing 22 is a pad or gasket 34 of nonconducting material, such as asbestos, to prevent the transmission of heat from the power element to the fuel tank. Bushings 35, also of asbestos, encircle the rearward ends of the cylinders 24 and 25 and seat in recesses 36 in the crank casing to minimize the flow of heat from the engine cylinders to the crank casing.

The interior of the crank casing 22 is divided into a plurality of crank chambers, three in the present instance designated 37, 38 and 39, by walls 40 arranged at spaced points within the crank casing. The walls 40, together with the outer walls 41 of the crank casing, serve as supports for a crank shaft 42 which extends entirely through the crank casing and carries on one exposed end lugs 43 for interlocking engagement with clutch members 44 of a crank 45 whereby the crank shaft may be rotated for starting the engine element of the tool.

The crank shaft has three crank pins 46, 47 and 48 each carrying a connecting rod 49 of which two are connected to pistons 50 and 51 in the cylinders 24 and 25 and the remaining rod is connected to a plunger 52 reciprocable in a piston chamber 53 in the percussive cylinder 26. The power element of the tool operates on the two cycle principle and each piston 50 and 51 is provided on its outer end or head with a baffle 54 to cause the incoming fuel charge to swerve downwardly into the lower portions of the cylinders 24 and 25 and thereby avoid undue loss of unburned fuel through the exhaust ports 55 in the engine cylinders.

The fuel charge is ignited in the cylinders 24 and 25 by sparking plugs 56 suitably attached to the lower portions of the cylinders, and the sparking periods are controlled by a timer 57 attached to an end of the crank shaft 42. The timer 57 may be connected, in a well known manner, to a coil 58 attached to the side of the percussive tool and having a cable 59 which may lead to a source of electrical supply, as for example a battery (not shown).

As a preferred arrangement each engine cylinder is provided with an individual fuel metering device arranged entirely within the casing of the percussive tool. These devices, of which only one is shown and designated 60, are arranged in the upper portion of the crank casing 22 directly

between the fuel tank 23 and the adjacent crank chambers 37 and 38 wherewith they communicate through passages 61 in the crank casing.

Each metering device comprises a cylindrical member 62 which is disposed in a recess 63 in the crank casing and having a flange 64 at its upper end which is clamped between the gasket 34 and a shoulder 65 in the recess for holding the metering device fixedly in position. In the central portion of the member 62 is a hub 66 which is joined to the body of the member 62 by ribs 67 cooperating with the body portion of the member and the hub to define passages 68 through which the air constituent of the fuel charge passes to the passage 61 and thus to the associated crank chamber. The air utilized for this purpose is conveyed to the passages 68 by channels 69 extending through columns 70 within the fuel tank 23, and in the rearward ends 20 of the channels 69 are screen plugs 71 to prevent the entrance of abrasive matter into the channels 69.

The air flow from the channel 69 to the passage 61 is controlled by a poppet valve 72 which seats against the lower end surface 73 of the cylindrical member 62 and has an upwardly extending stem 74 slideable in the bore 75 in the hub 66. In the upper end of the stem 74 is an annular groove 76 to receive a split collar 77 that seats into a depression 78 of a sleeve 79 disposed about the stem 74, and on the periphery of the sleeve 79 is a flange 80 that serves as a seat for a spring 81 seated upon the ribs 67 to normally press the valve 72 against the surface 73. A suitable space 82 exists between the upper end of the hub 66 and the sleeve 79 to permit of a limited degree of endwise movement of the valve for opening communication between the passages 68 and 61.

An additional function of the valve 72 is to control communication between the passage 61 and the interior of the fuel tank 23. The cylindrical member 62 is accordingly provided with a plurality of channels 83 which extend from one end to the other of the cylindrical member and have their outlet openings lying within the compass of the valve 72 so that when the valve is seated against the surface 73 the outlet ends of the channels 83 will be fully sealed thereby.

In order to prevent clogging of the channels 83 by such particles of foreign matter as may be entrained in the fuel, said channels are preferably of considerably larger cross sectional area than the flow area necessary for the fuel requirements of the power element of the tool, and filler pins 84 are disposed in the channels 83 to cooperate with the walls thereof for defining restricted annular passages 85 through which fuel may flow to the passage 61. The pins 84 are suspended in the channels 83, having heads 86 that rest upon shoulders 87 at the upper ends of the channels 83.

As a preferred arrangement the fuel is introduced into intermediate portions of the channels 83 by passages 88 extending through the member 62 and the gasket 34 and opening into an annular supply chamber 89 on the lower end of the fuel tank 23. The supply chamber 89 is in open communication with the interior of the fuel tank through passages 90. Between the supply chamber 89 and the passages 88 is a screen 91 to prevent foreign matter from entering the channels 83 and the associated crank chamber where the fuel charge is thoroughly mixed and from whence it flows to the engine cylinders

through passages 92 leading from the crank chambers to points in the cylinders approximately in the same transverse plane as the exhaust ports 55.

Although the percussive tool is provided, at various points, with insulating members adapted to prevent the transmission of heat from the engine cylinders to adjacent portions of the structure it has been found to be advantageous to provide means for causing the quick dissipation of the heat of combustion. To this end the percussive tool is provided with a blower or fan 93 for directing jets of air against the sides of the cylinders 24 and 25. The fan 93 is driven by the crank shaft 42 and is mounted upon a shaft 94 carrying a pinion 95 that meshes with a gear 96 keyed to a web 97 of the crank shaft.

The fan is arranged in a chamber 98 in the side of the crank casing and a cover 99 for the chamber 98 supports an anti-friction bearing 100 for an end of the shaft 94. A similar bearing 101 is disposed in the crank casing adjacent the pinion 95 to support the opposite end of the shaft 94.

In order to subject the fuel in the tank 23 to the cooling effect of the air impelled by the fan 93 and thus further reduce the chances of vaporization of fuel in the tank, the inlet passage 102 for the fan is formed along the side of the fuel tank and is of considerable width so that it extends along the major portion of such side. Owing to this arrangement the inner wall 103 of the passage, and which wall forms a bounding surface for the fuel tank, will be kept at a low temperature and thereby exert a cooling effect upon the fuel.

The air discharged by the fan 93 passes into the chamber 98, thence through a discharge port 104 in the crank casing and a nozzle 105 having two diverging branches 106 which are positioned so as to direct the air against the sides of the engine cylinders 24 and 25.

In addition to the cylinder 26 and the plunger 52 the percussive element comprises a hammer piston 107 reciprocable in the piston chamber 108 containing the plunger 52 for delivering blows to the working implement 21, the shank of which extends into the front end of the piston chamber and carries a collar 109 for engagement with a steel retainer 110 carried by a front head 111 attached to the cylinder 26 for guiding the working implement. The hammer piston 107 is hollow having a cavity 112 to receive a reduced extension 113 of the plunger wherewith the hammer piston is in slideable and non-interlocking engagement.

The peripheral surface of the cavity 112 serves as a guide for the extension 113 and the rearward end portion 114 of the plunger is enlarged and in slideable engagement with the wall of the piston chamber. The plunger 52 is thus guided by the walls of the piston chamber and of the cavity 112. By reason of this construction an annular chamber 115 will exist around the plunger 52 between the enlargement 114 thereof and the rearward end surface 116 of the hammer piston.

The portion of the cavity 112 forwardly of the plunger 52 constitutes a pressure chamber 117 in which air is alternately compressed to transmit the force of the plunger to the hammer piston on the power stroke of the plunger and expanded to a sub-atmospheric value on the return stroke of the plunger to cause the hammer piston 107 to

be retracted to the starting position of the power stroke.

In order to avoid the necessity of maintaining a perfect seal between the peripheral surface of the plunger 52 and the cooperating surface of the hammer piston for the sake of preventing a diminution of the air entrapped in the pressure chamber 117 it is contemplated to effect an intermittent admission of atmospheric air into the pressure chamber 117 to compensate for such air as may be forced from the cavity 112 during the power stroke of the plunger of the hammer piston and during which time the air in the pressure chamber 117 will, of course, be materially compressed.

In the form of the invention illustrated, the air utilized for this purpose is derived from the crank chamber 39 which the air enters through a passage 118 in a rib 119 extending through the fuel tank and having a strainer plug 120 at its outer end to filter the air.

The crank chamber 39 is in direct communication with the interior of the plunger 52, and in the enlarged portion 114 of said plunger are radial ports 121 which, in the extended position of the plunger, communicate with an annular groove 122 in the wall of the piston chamber to permit the passage of air from the crank chamber into the annular chamber 115.

Communication is afforded between the annular chamber 115 and the pressure chamber 117 through channels in the periphery of the plunger and in the adjacent contacting surface of the hammer piston. The channels in the plunger are in the form of longitudinally extending grooves 123 of such length that their rearward ends will be exposed by the skirt of the hammer piston during the rearward stroke of the plunger and during which time the hammer piston will assume its most forwardly position with respect to the plunger. The grooves 123 preferably extend to points near the front or lower end of the plunger and are in constant communication with an annular groove 124 near the rearward end of the cavity 112, and from the groove 124 extend grooves 125 forwardly along the wall of the cavity 112 to a second annular groove 19 adjacent the pressure chamber 117.

Thus, in practice, when the plunger 52 starts forwardly on the working stroke its initial movement will take place relatively to the hammer piston and will cause the rearward ends of the grooves 123 to be covered by the adjacent portion of the skirt of the hammer piston. Air will then be entrapped in the pressure chamber 117 and be compressed, since it serves as the medium through which the force of the plunger 52 is transmitted to the hammer piston, and when the plunger reaches the end of its working stroke the hammer piston will be projected forwardly against the working implement 21 to deliver its blow.

The forward movement of the hammer piston, relatively to the plunger 52, will cause the rearward ends of the grooves 123 to be uncovered by the hammer piston and air will then again be admitted into the pressure chamber 117 through the grooves 123, 124 and 125. This admission of make-up air into the pressure chamber 117 takes place during the interval in which the ports 121 are in registry with the groove 122.

Upon reversal of the plunger the ports 121 are drawn out of registry with the groove 122 and the ensuing rearward movement of the plunger 75 will create a sub-atmospheric pressure in the

chambers 115 and 117 and cause the hammer piston to follow the plunger rearwardly.

The front end of the piston chamber, below the hammer piston 107, is normally maintained in communication with the atmosphere so that atmospheric pressure will be constantly present forwardly of the hammer piston to impel it rearwardly in accordance with the rearward movement of the plunger 52. The air serving this function is, in the present instance, conveyed 10 from the crank chamber 39 by a passage 126 in the crank casing 22 and the cylinder 26 and opening into the front end of the piston chamber 108.

Interposed in the passage 126 is a valve 127 of the rotary plug type having a lever 128 whereby it may be manipulated, and in the valve 127 is a passage 129 to normally afford communication between the associated portions of the passage 126. The valve 127 also has a port 130 which, when the valve is in position in which the passage 129 is out of registry with the passage 126, communicates with a portion of the passage 126 leading from the crank chamber 39 to the valve. In this position of the valve the passage 129 opens into an annular groove 131 within the piston chamber and said groove 131 is so located that when the hammer piston 107 reaches the working implement 21 ports 132 in the wall of the hammer piston will be in communication with the groove 131.

Normally, the valve 127 occupies a position to prevent communication between the passage 126 and the groove 131 and is only positioned to admit air into the groove 131 and, therefore, into the pressure chamber 117 whenever it is intended to avoid the delivery of blows against the working implement, as for example when shifting the percussive tool from one drilling site to another while the engine element is in operation. In such case the valve 127 is rotated to a position in which the port 130 is in communication with the uppermost portion of the passage 126. Air will then flow through these passages and through the groove 131 and the ports 132 into the front end of the cavity 112 to maintain atmospheric pressure therein. The hammer piston 107 will then remain at rest in the forward end of the piston chamber 108 and will be undisturbed by the movement of the plunger, since then the pressures in the forward end of the piston chamber and within the cavity 112 will be the same.

Preferably, a port 133 is provided between the portion of the passage 126 lying forwardly or below the valve 127 and the adjacent portion of the piston chamber 108 so that when the working implement is removed from the path of the hammer piston, and in consequence of which the hammer piston 107 will rest upon the forward wall of the piston chamber 108, the ports 132 will register with the port 133 to maintain the chamber 117 in communication with the atmosphere and thereby avoid a tendency, on the part of the hammer piston, to reciprocate while the percussive tool is running idle.

In order to assure a plentiful supply of lubricant to the bearings of the crank shaft 42 an oil chamber 134 is formed in the upper surface of the crank casing 22 and suitable oil passages 135 lead from the oil chamber to the bearings of the crank shaft. The oil passages 135 all extend in a downwardly direction so that oil will readily flow from the oil chamber 134 to the bearings by gravity. A filling opening 136 is formed in a wall of the crank casing for replenishing the supply

of oil in the chamber 134 and said opening 136 is sealed by a plug 137.

I claim:

1. A percussive tool, comprising a casing having a piston chamber, a hammer piston in the piston chamber having a pressure chamber, and a plunger slidable in the piston chamber and in the pressure chamber for actuating the hammer piston and cooperating with the hammer piston to create a sub-atmospheric pressure in the pressure chamber to cause the hammer piston to follow the plunger in one direction.
2. A percussive tool, comprising a casing having a piston chamber, a hammer piston in the piston chamber having a pressure chamber, a plunger slidable in the piston chamber and in the pressure chamber for actuating the hammer piston and cooperating with the hammer piston to create a sub-atmospheric pressure in the pressure chamber and thereby cause the hammer piston to follow the plunger in one direction, and means on the plunger and the hammer piston cooperating with each other to intermittently admit atmospheric air into the pressure chamber.
3. A percussive tool, comprising a casing having a piston chamber, a hammer piston in the piston chamber having a pressure chamber, a plunger slidable in the piston chamber and in the pressure chamber for actuating the hammer piston and cooperating with the hammer piston to create a sub-atmospheric pressure in the pressure chamber and thereby cause the hammer piston to follow the plunger in one direction, passages in the plunger to convey atmospheric air into the pressure chamber, and means on the hammer piston to control the passages.
4. A percussive tool, comprising a casing having a piston chamber, a hammer piston in the piston chamber having a pressure chamber,

plunger slidable in the piston chamber and in the pressure chamber for actuating the hammer piston and cooperating with the hammer piston to create a sub-atmospheric pressure in the pressure chamber and thereby cause the hammer piston to follow the plunger in one direction, passages in the cooperating surfaces of the plunger and the hammer piston to convey atmospheric air into the pressure chamber, and means on the hammer piston cooperating with the plunger to control the passages.

5. A percussive tool, comprising a casing having a piston chamber, a hammer piston in the piston chamber having a pressure chamber, a plunger slidable in the piston chamber and the pressure chamber for actuating the hammer piston and cooperating with the hammer piston to create a sub-atmospheric pressure in the pressure chamber to cause the hammer piston to follow the plunger during alternate strokes of the plunger, and manually operable means for selectively introducing atmospheric air into the pressure chamber.

6. A percussive tool, comprising a casing having a piston chamber, a hammer piston in the piston chamber having a pressure chamber, a plunger slidable in the piston chamber and the pressure chamber and cooperating with the hammer piston to create a sub-atmospheric pressure in the pressure chamber to cause the hammer piston to follow the plunger during alternate strokes of the plunger, a passage in the casing to convey atmospheric air to the front end of the piston chamber, a passage in the hammer piston communicating with the pressure chamber, and a manually operable valve to selectively control communication between the passages.

WILLIAM A. SMITH, SR.
